UNITED STATES PATENT OFFICE.

CHARLES E. GABBY, OF CHENEY, WASHINGTON.

DRYING-RACK.

1,111,892.

Specification of Letters Patent. Patented Sept. 29, 1914.

Application filed October 2, 1913. Serial No. 792,997.

To all whom it may concern:

Be it known that I, CHARLES E. GABBY, a citizen of the United States, residing at Cheney, in the county of Spokane and State of Washington, have invented new and useful Improvements in Drying-Racks, of which the following is a specification.

One of the objects of this invention is to utilize the heat incidentally created by operation of a heating means having a wholly different utility for the purpose of quickly drying articles of apparel, towels and the like, and to provide a novel form of supporting means therefor which may be assembled 10 or dis-assembled and attached or detached with ease and facility.

A cooking range is generally located in close adjacency but in spaced relation to a wall or like structural part and the temperature in this space is much higher than 20 temperature in the remainder of the compartment in which the range is located and there is usually created in such space a generally upward current of hot air which 25 slowly rises as colder air ingresses at the open sides, and this incidentally heated space has not heretofore been available for 30 convenient use because of its restricted area and the lack of supporting means adapted for location therein.

It is one of the objects of my invention to provide a support available for use in such space so as to take advantage thereof but one which is simple in construction and 35 easily attachable to a range or the like so as to suspend such articles in the most effective position in such space for quickly drying the same.

Other objects and features of the invention 40 will be more fully described in connection with the accompanying drawing and will be more particularly pointed out in and by the appended claims.

In the drawing:—Figure 1 is a view in 45 side elevation of a cooking range disposed adjacent a wall of the compartment or room in which it is located, with my invention applied thereto. Fig. 2 is a rear view thereof. Fig. 3 is a perspective view of the device of 50 my invention detached from the range.

Like characters of reference designate like parts throughout the different figures of the drawing.

As shown, the device of my invention is 55 applied to a cooking range 1, having an upper horizontal marginal portion 2, and ver-

tical side marginal portions 3. The range 1, is disposed adjacent a wall 4, but in such spaced relation therewith as to leave an intervening space 5. Because of this relatively restricted space, the temperature 60 therein exceeds that of the remainder of the interior in which the range is located and the tendency of the air therein is to rise so that air is drawn in from the ends of the 65 range and an upward current of slowly rising air is maintained behind the range.

An article, such as a towel 6, is suspended in the most effective position in order to receive the utmost benefit of the hot air, such 70 position being at a considerable elevation from the floor or the base of the heating means. It will be seen that the range functions in its usual capacity and that the heat given off in the space 5, is incidental to the 75 normal operation of the range and is usually lost.

Supporting means is provided for pendantly hanging articles to be dried in the most effective position in the space 5, in order to 80 obtain a maximum drying efficiency, and such means will now be described in detail. Said means comprises as shown, a length of wire 7, which is preferably straight, and which is provided with bent ends 8, extending 85 inwardly from the straight or supporting portion 7, to form rearwardly extending arms adapted to maintain the supporting portion 7, in proper spaced relation rearwardly from the range. The terminals of 90 the arms are provided with fastening elements, integrally formed therewith which are preferably in the form of hooks 9. The wire of which the support is formed is sufficiently resilient so that when the hooks 9 are 95 secured to the vertical end margins 3, they will have to be sprung thereabout. One or more hanger supports 10, preferably formed of wire, are provided with eyes 11, adapted to be strung onto the main support and be 100 rotatively connected therewith. The free ends of the supports 10, are provided with terminal fastening elements which may take the form of hooks 12, which are adapted to be secured over the upper marginal portion 105 2, so as to suspend the main supporting part 7, in a substantially horizontal position, as clearly shown.

By suspending the device near the top of the range, and by the novel construction 110 shown, said device may not only be readily secured in place, but when in position, the

same is in the most effective position to subject the articles held thereby to the most highly heated portion of the space 5.

It is believed that the utility and advantages of my invention will be fully understood from the foregoing and while I have shown one specific form of my invention, I do not wish to be limited thereto except for such limitations as the claims may import.

10 I claim:—

In a clothes or like article supporting means, as an article of the class described, a supporting structure having top horizontal and end vertical marginal portions, a length 15 of wire having its ends extending rearwardly thereof and provided with terminal hooks

adapted to be sprung into grip with said end vertical margins to form a horizontal support, and one or more hanger wire supports rotatively connected with said wire support 20 and having hooked end for engaging said horizontal margin to pendently sustain said support in a horizontal position, substantially as described and for the purposes set forth.

35

In testimony whereof I hereunto affix my signature in the presence of two witnesses.

CHARLES E. GABBY.
